UNITED STATES PATENT OFFICE.

PETER H. JACKSON, OF SAN FRANCISCO, CALIFORNIA.

SMOKE-CONSUMING FURNACE.

SPECIFICATION forming part of Letters Patent No. 268,682, dated December 5, 1882.

Application filed June 29, 1882. (No model.)

To all whom it may concern:

Be it known that I, PETER H. JACKSON, of the city and county of San Francisco, State of California, have invented Improvements in 5 Smoke-Consuming Furnaces; and I hereby declare the following to be a full, clear, and exact description thereof.

My invention relates to certain improvements in the combustion of fuel, and to apparatus by which it may be carried out.

It consists of a fire-box to contain the fuel, with exterior and interior passages, by which air is supplied at the bottom and top, and through the fuel from the sides.

15. My invention also consists of certain details of construction, as hereinafter fully described, and specifically set out in the claims.

A self-regulating valve or damper in the escape-pipe controls the discharge of the products of combustion.

25. Referring to the accompanying drawings for a more complete explanation of my invention, Figure 1 is a vertical section of an apparatus showing the application of my invention. Fig. 2 is a perspective view of the fuel-chamber. Fig. 3 is a view of the central cone. Fig. 4 is a horizontal section of the fuel-chamber, taken through xx , Fig. 1. Figs. 5, 6, and 7 show the invention as applied to horizontal 30 boilers. Fig. 8 shows the return-pipe for gases in connection with a furnace.

A is a fuel-chamber, having the grate B at the bottom. The fuel-chamber is inclosed by an outer casing, C, situated at such a distance 35 from it as to leave an air-space around the fuel-chamber, through which air may pass up freely. This air-space extends up from the level of the grate to the line of the top of the fuel, and is subdivided into two sets of spiral flues, D and E. One set of these flues, D, have closed sides the entire length, being open only at the bottom and top. The other alternate 40 set of flues, E, have slots or openings a on the inner side into the fuel-chamber, through which air is admitted to the fuel at the sides. Both sets of these flues are drawn inwardly 45 toward the center at the top, so as to discharge a large body of heated air with a whirling motion over the top of the fuel.

50. A central tube or passage, F, extends up through the fuel-space, and has vertical open-

ings b , through which air is admitted to the fuel from the inside as well as the outside. A cone, G, having spirally-placed wings c , is fixed above the passage F, so that the air which escapes through it will also have a whirling motion imparted to it, similar to that discharged by the exterior flues, D and E. These flues or passages all open into a chamber, H, below the grate and within the outer casing, C. The bottom of this casing has an opening, into which is fitted the end of the large air-supply pipe I. This pipe may receive and convey air from any suitable blast apparatus or device, or it may be cut off at the dotted line ab and admit simply a natural draft. The return pipe or flue J, the use of which will be described hereinafter, enters the side of this air-pipe, and is curved, so that its discharge end is in the center of this air-pipe and just below the point where it opens into the chamber H; or the air-pipe I may be central and the pipe J outside. In this latter case the space between I and J will be quite small. A distributing-cone, K, is fixed so as to regulate the discharge 75 from the pipe J at will. Above the fuel-chamber is a combustion-chamber, L, inclosed by a casing, M, which is fastened upon the top of the casing C, and above this is another smaller drum, N, from which the escape pipe or flue O leads to the chimney I'. In the upper part of the chamber L is a flaring-mouthed deflector, P, extending nearly to the circumference of the chamber. From its center the return pipe or flue J leads upward, passing out 80 through the side of the drum M, thence downward into the air-supply pipe and to a point beneath the chamber H, as before described. This construction is precisely the same when applied to a straw-burning furnace, as shown in 85 Fig. 6, except that the shape of the chambers are somewhat different and the boiler-tubes form a part of the return system for the unconsumed gases; or the boiler-tubes may be the exit for the gases from the fire and then return through 90 another pipe to beneath the grate-bars, to pass through the fire.

The operation will then be as follows: Fuel being placed in the chamber A and ignited, air will be drawn by natural draft; or it may be otherwise supplied through the passage I, being controlled by suitable dampers. This air

passes into the chamber H and through the grate B to the fuel, and after the latter is ignited the air which passes through the exterior spiral passages, D and E, and the interior passage, F, will be heated, part of it passing into the fuel chamber through the openings a and b, and the remainder being delivered with a whirling motion inwardly and outwardly over the top of the fuel, where it meets the unconsumed gases escaping therefrom, thus supplying fresh oxygen at the point where it is most needed. In order to still further consume these gases and produce the most complete combustion, they are collected by the hood P and pass into the pipe J. The draft from below, caused by the heated air passing through the fuel, will return these unconsumed gases to the point below the chamber H, where they are discharged around the distributor K and mixed with the column of inflowing air in the pipe I, passing into the chamber H, and thence into the fuel-chamber, to be consumed. These hot returning gases also assist in heating and rarefying the inflowing air, which supplies combustion, so that the temperature is kept up and the combustion is much more perfect. In the application to steam-boilers and some kinds of furnaces it may be found desirable to introduce a jet of steam through the center of the pipe I or J to increase the draft; or this may be effected by any other well-known means.

Within the chimney or escape-pipe O is fixed a valve or damper, R, having an exterior operating-arm, S. This arm is connected with a body of mercury, which is contained in a tube or coil, T, and is so placed that it will be expanded or contracted as the heat varies, or with other automatic regulator which is operated by the passing heat. The opening or closing of this damper R regulates the passage of the products of combustion to the chimney. These escape around the exterior edge of the hood P in the chamber M above the fire-place A, passing thence through the chamber N and into the flue or pipe O to the chimney.

Having thus described my invention, what I claim as new, and desire to secure by Letters Patent, is—

1. In a heating apparatus, the fuel-chamber A, the exterior casing, and the air-passages E, surrounding the chamber A, and having slots or openings a, through which air may be admitted to the fuel from the sides, substantially as herein described. 50

2. In a heating apparatus, the fuel-chamber A, with its spirally-arranged surrounding air-passages D and E, discharging air above the fuel to mix with the gases arising therefrom, substantially as herein described. 55

3. In a heating apparatus, the fuel-chamber A, with its central air-passage, F, having side openings, b, and the distributing-cone G, substantially as herein described. 60

4. In a heating apparatus, the fuel-chamber A, having the central perforated air-passage, F, and the surrounding passages D and E, the alternate ones being perforated, and all discharging air above the fuel, substantially as herein described. 65

5. In a heating apparatus, the fuel-chamber A, having the central and the surrounding air-passages, with their spirally - arranged discharge-passages opening above the fuel, substantially as and for the purpose herein described. 70

6. In a heating apparatus, the fuel-chamber A, with its central and surrounding air and draft passages, the chamber H, to receive air and unconsumed gases from the pipes I and J, 80 as shown, the chamber M, and collecting-hood P, in combination with the escape flue or passage O, valve R, and automatic opening and closing device, substantially as herein described. 85

7. In a heating apparatus, the fuel-chamber A, in combination with the upper chamber, L, and the collecting-hood P, pipe J, leading from the chamber N to the chamber H, and the air-pipe I, surrounding the discharge end of pipe J, substantially as and for the purpose herein described. 90

In witness whereof I hereunto set my hand.

PETER H. JACKSON.
